J. H. DEVINE

COMBINATION JACK AND JOINTER PLANE

Filed June 1, 1923

Patented May 27, 1924.

1,495,579

UNITED STATES PATENT OFFICE.

JOHN H. DEVINE, OF DENVER, COLORADO.

COMBINATION JACK AND JOINTER PLANE.

Application filed June 1, 1923. Serial No. 642,741.

To all whom it may concern:

Be it known that I, JOHN H. DEVINE, a citizen of the United States, residing at Denver, the city and county of Denver, and 5 State of Colorado, have invented certain new and useful Improvements in Combination Jack and Jointer Planes; and I do declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

This invention relates to improvements in carpenters' planes, and has special reference to an attachment by means of which the stock can be increased and whereby an ordinary jack-plane can be readily converted into and used for a jointer.

In order to be in position to do the various jobs that are necessary in building and other carpenter work, it is essential that a carpenter shall have the proper tools. Among other things, he must have a jack-plane and a jointer-plane. The main distinction between these two types of planes is one of length, a jack-plane being anywhere from 20 12 to 17 inches in length, while a jointer-plane is from 28 to 30 inches long. The jack-planes, as manufactured and sold today, are all of substantially the same length and width, being approximately 14 inches 25 long and $2\frac{3}{8}$ inches wide, while the jointer-planes are substantially 24 inches long and $2\frac{3}{4}$ inches in width and weight approximately eight pounds.

As the only real distinction between a 40 jack-plane and a jointer is one of length only, it is apparent that, by providing a suitable attachment that can be readily secured to and removed from the jack-plane and by means of which the effective length of the 45 stock can be increased, the jack-plane can be used as a jointer.

It is the object of this invention to produce an attachment which shall be light and rigid, and which shall be provided with 50 means by which it can be secured to a jack-plane of ordinary construction for increasing the effective length thereof. By means of my attachment, the jack-plane can be made to do the work of a jointer-plane and 55 therefore it will be unnecessary for the carpenter to go to the expense of buying more

than one plane. As a jointer-plane weighs about eight pounds, while the attachment is comparatively light, it is evident that less weight will have to be carried about. 60

In order to more clearly show and describe my invention, I shall have reference to the accompanying drawing in which the preferred form thereof is shown and in which:

Fig. 1 is a perspective view of a jack-plane, to which my attachment has been applied;

Fig. 2 is a section taken on line 2-2, Fig. 1;

Fig. 3 is a top plan view of my attachment 70 looking in the direction of arrow 3, in Fig. 4.

Fig. 4 is a side view of my attachment; and

Fig. 5 is a bottom plan view looking in 75 the direction of the arrow 5 in Fig. 4.

The same reference characters will be used to designate the same parts through the several views.

Numerical 1 represents the stock of a jack-plane which is provided with the ordinary iron 2, breaker iron 3, wedge 4, and toot 5. My removable extension member 5 is made of cast metal or of pressed steel and has a flat bottom or sole 6 whose length is approximately 24 inches and whose outside width is about $2\frac{3}{4}$ inches. The sole 6 is formed in two parts, joined by vertical sides 7 which are upwardly arched in the manner shown in Figs. 1 and 4. The distance between the inner surfaces of sides 7 is equal to the width of the jack-plane and the distance between the inner ends of the sole sections 6 (indicated by numerals 8 and 9) is equal to the length of the sole of the 90 stock of the jack-plane. The metal portions marked 10 and 11 are pressed upwardly in the manner indicated in Fig. 4 to a distance which is equal to or slightly greater than the thickness of the material 95 in the sole of the jack-plane stock. The upwardly pressed portions 10 and 11 are each provided with three spaced holes for the reception of the screws 12, 13 and 14, the purpose of which will hereinafter appear. The 100 ends of the jack-plane are perforated and threaded for the reception of screws 13 which serve to clamp the jack-plane to the attachment in the manner shown in Fig. 2. As it is essential that the sole of the plane 110 and that of the attachment shall be in one plane, the screws 12 and 14 are provided for

the purpose of making the necessary adjustments. Screws 12 and 14 are threadedly connected to the plane attachment, while screw 13 is threaded to the sole of the plane. 5 Therefore by means of these three screws at each end, the plane and the attachment may be accurately adjusted so that the surfaces of the soles will coincide. The screws 12 and 14, after they have been once adjusted 10 to fit a certain plane, will not have to be moved, and therefore the attachment can be secured to the plane by merely operating the screw 13.

It is my intention to form the attachment 15 from a piece of steel plate about $\frac{1}{16}$ of an inch in thickness, as they can then be pressed out by means of a die. They can, however, be cast from steel or a good grade of cast-iron. The arched sides 7 give the device 20 the requisite rigidity so that the sole will not become curvy when subjected to ordinary strains.

From the foregoing, it will be apparent 25 that I have invented an attachment that can readily be attached to a jack-plane and which will convert the same into a jointer-plane. These attachments cost only a fraction of what a jointer-plane costs and weighs a great deal less.

Having now described my invention, what 30 I claim is:

1. An article of manufacture comprising a pair of plane soles spaced apart and connected along their outer edges by means of parallel ribs or flanges, said soles having 35 their inner ends offset to provide recessed portions adapted to receive the ends of a jack-plane; and adjusting screws threadedly connected to each offset portion.

2. An article of manufacture comprising 40 a pair of plane soles spaced apart and connected along their outer edges by means of parallel ribs or flanges, said soles having their inner ends offset in an upward direction to provide recessed portions adapted 45 to receive the ends of a jack plane, a screw rotatably connected to the center of each offset portion, said screw being freely rotatable therein and adapted to be threadedly connected to the jack plane, and an adjusting screw threadedly connected with each offset portion on each side of the first-mentioned screw, said screws being adapted 50 to engage respective sides of the jack plane for purpose of adjustment.

55 In testimony whereof I affix my signature.

JOHN H. DEVINE.
